UNITED STATES PATENT OFFICE.

JAHN BRANECKY, OF ELDRED, PENNSYLVANIA.

SUNKEN-VESSEL-LOCATING DEVICE.

1,204,842.

Specification of Letters Patent. Patented Nov. 14, 1916.

Application filed February 2, 1916. Serial No. 75,692.

To all whom it may concern:

Be it known that I, JAHN BRANECKY, a citizen of the United States of America, residing at Eldred, in the county of McKean

5 and State of Pennsylvania, have invented certain new and useful Improvements in Sunken-Vessel-Locating Devices, of which the following is a specification.

This invention relates to new and useful 10 improvements in sunken vessel locating devices.

The primary object of the invention is the provision of an inexpensive device adapted to be carried by a boat or vessel for the 15 purpose of not only locating its position when sunk to the bottom of the water but also to sound an audible alarm whereby its approximate location is brought to the attention of near-by vessels.

20 A further object of the device is to provide an attachment for boats so that their submerged position is readily noted and provision made for assisting in raising the vessel, the device being serviceable both in 25 the time of peace and war.

The device therefore broadly contemplates a floating bell buoy adapted for automatic ringing by the action of the waves and normally carried freely positioned upon 30 the deck of a vessel, the buoy being attached thereto by a desirable length of line whereby upon sinking of the vessel, the buoy rides upon the waves and sounds an alarm for denoting the position of the sunken 35 craft.

With these general objects in view and others that will appear as the nature of the invention is better understood, the same consists in the novel combination and arrangement of parts hereinafter fully described, 40 illustrated in the accompanying drawings and then claimed.

In the drawings forming a part of this application and in which like designating 45 characters refer to corresponding parts throughout the several views, Figure 1 is a radial sectional view through one of the buoys, the bell being shown in side elevation, and Fig. 2 is a top plan view thereof.

50 A plurality of floats or buoys 13 are provided and each comprises a thin metallic casing 14 of light weight having an air or gas containing chamber 15 therein being of flattened spheroidal shape.

55 A post 16 is provided extending axially of the shell 14 at the side thereof which is

normally arranged uppermost, a bell 17 being arranged encircling the said post and secured to the top thereof by means of a 60 screw 18.

An attaching ring 19 is carried by the casting 14 upon the opposite side thereof from and in axial alinement with the aforementioned post 16 and is provided with a flexible attaching means that may extend to a 65 sunken vessel.

Clappers 25 are pivoted to lugs 26 arranged around the periphery of the buoy shell 14 and at equal distances apart having hammers 27 at their free ends adapted for 70 striking the bell 17. Flattened feet or paddles 28 extend angularly from the clappers 25 and outwardly of the pivoting lugs 26 thereof, the paddles 28 being normally held horizontal and the clappers 25 out of engagement with the bell 17 by means of 75 U-shaped springs 29 secured to the shell 14 between the lugs 26 and engaging the adjacent sides of the said clapper and paddle.

When the buoy 13 is arranged floating 80 upon the water the weight of the line as well as its attachment to the sunken vessel will retain the buoy upright and with the bell 17 uppermost, while the paddles 28 will be positioned approximately upon the surface 85 of the water when the latter is perfectly calm but the action of any slight waves upon the water will move the paddles 28 relatively to each other and upon their pivot lugs 26 so as to bring the hammers 27 in 90 violent contact with the bell 17, thus sounding an audible alarm. Each of the buoys 13 being provided with a plurality of clappers, will result in a substantially continuous ringing of the bell 17 of each buoy 95 13 so that such an operation of all of the buoys will provide a loud signal whereby the presence of the buoys will be located by any passing vessel.

While the form of the invention herein 100 shown and described is what is believed to be the preferable embodiment thereof, it is nevertheless to be understood that minor changes may be made in the form, proportion and details of construction without departing from the spirit and scope of the invention as hereinafter claimed.

What I claim as new is:—

1. A device of the class described comprising a hollow float of spheroidal shape, 110 a bell-supporting post carried by said float, a bell carried by said post, line attaching

means carried by the float, a plurality of clappers pivotally mounted on the float around the equator thereof, paddles projecting from said clappers normally positioned in a plane parallel to the equator of the shell, and springs for holding said paddles in their normal positions and the clappers out of contact with the bell.

2. A vessel locating device comprising a metallic hollow float of spheroidal shape, an attaching ring axially positioned upon the lower side of the said float, a post axially projecting from the opposite side of the said float, a bell secured to the said post, clappers for the said bell pivoted equal distances apart adjacent the outer edge of the said float, paddles projecting angularly from the said clappers normally horizontally positioned when the float is at rest with the clappers out of engagement with the said bell, and U-shaped positioning springs for the said clappers and paddles carried by the upper side of the said float adjacent the points of

pivotal connection of the said clappers therewith.

3. A device of the class described comprising a hollow metallic spheroidal shell, a ring and a post projecting from opposite axial points upon the said shell, a bell encircling the said post and secured to the outer free end thereof, pairs of lugs upon the post carrying side of the said shell adjacent its equator, clappers pivoted to the said lugs and having engaging hammers for the said bell at their free ends, paddles angularly projecting from the said clappers outwardly of the said lugs and normally positioned in a plane parallel to that of the said equator of the shell and with the hammers out of engagement with the said bell, and normally positioning U-shaped springs carried by the shell between the said lugs in resilient contact with the adjacent clapper and paddle.

In testimony whereof I affix my signature.

JAHN BRANECKY.

Copies of this patent may be obtained for five cents each, by addressing the "Commissioner of Patents, Washington, D. C."
